The ornamental design for an electric hair straightening comb, as shown and described.

DESCRIPTION

FIG. 1 is a perspective view of an embodiment of an electric hair straightening comb in accordance with the present invention.

FIG. 2 is a right side view thereof.

FIG. 3 is a left side view thereof.

FIG. 4 is a top view thereof.

FIG. 5 is a bottom view thereof.

FIG. 6 is a back view thereof; and,

FIG. 7 is a front view thereof.
